UNITED STATES PATENT OFFICE.

WILLIAM JAY TUROFF AND ELISE AUVRAY BESANCON, OF NEW YORK, N. Y.

DESIGN FOR A BOUDOIR CAP.

Application filed July 19, 1923. Serial No. 6,806. Term of patent 3½ years.

To all whom it may concern:

Be it known that we, WILLIAM J. TUROFF and ELISE AUVRAY BESANCON, both citizens of the United States, and residents, respectively, of the city of New York, borough of the Bronx, in the county of Bronx and State of New York, and of the city of New York, borough of Manhattan, in the county and State of New York, have invented a new, original, and ornamental Design for Boudoir Caps, of which the following is a specification, reference being had to the accompanying drawings, forming part thereof.

The figure is a perspective view of a boudoir cap after it has been shaped, showing our new design.

We claim:

The ornamental design for a boudoir cap as shown.

WM. JAY TUROFF.
ELISE AUVRAY BESANCON.
